ATTORNEY

UNITED STATES PATENT OFFICE

HAROLD H. WAGNER, OF WAUSAU, WISCONSIN, ASSIGNOR OF ONE-HALF TO GEORGE A. WAGNER, OF WAUSAU, WISCONSIN

PISTON

Application filed January 4, 1929. Serial No. 330,165.

This invention relates to certain novel improvements in pistons and has for its principal object the provision of an improved construction of this character which will be 5 highly efficient in use and economical in manufacture.

It is among the objects of my invention to provide a piston which will be so constructed that the noise known as "piston 10 slap" which is caused by looseness of a piston in a cylinder will be obviated.

Another object of the invention is to provide a piston which will be so constructed that it will expand and contact in accordance with the engine heat.

A further object of the invention is to provide a piston of the above described type which will be so constructed that the wearing qualities thereof will be enhanced and a construction in which an arrangement will be provided that will effectively prevent leakage past the piston and also one in which scoring and freezing of the piston will be prevented.

25 A still further object of the invention is to provide a piston which will be arranged to increase the efficiency of operation of the engine or other similar devices in which it is arranged.

30 Other objects will appear hereinafter.

The invention consists in the novel combination and arrangement of parts to be hereinafter described and claimed.

The invention will be best understood by 35 reference to the accompanying drawing, showing the preferred form of construction and in which:

Fig. 1 is an elevational view depicting a 40 preferred form of construction for my improved piston;

Fig. 2 is a view partly in elevation and partly in section depicting a sleeve provided in my piston construction;

Fig. 3 is a view partly in elevation and 45 partly in section depicting the sleeve shown in Fig. 2 mounted in operative position on the main body of the piston; and

Fig. 4 is a fragmental perspective view 50 depicting a joint employed in the sleeve portion depicted in Fig. 2.

In the accompanying drawing wherein I have illustrated the preferred form of construction for my device 10 indicates the main body portion of my improved piston in which the usual journals such as 11 are provided for 55 the wrist pin. At the lower end of the skirt portion of the main body portion 10 an outwardly projecting flange 12 is provided. At the upper end of the skirt portion of the main body portion 10 an outwardly projecting flange 13 is provided and thus a groove 60 14 is defined on the periphery of the main body portion 10 between the flanges 12 and 13. Outwardly projecting rings 15 and 16 are formed on the main body portion 10 adjacent 65 the flange 13.

The skirt portion of my improved piston is formed from a sleeve that is indicated by 70 17 in the drawing. The sleeve 17 is split in the stepped manner indicated at 18 and which is best shown in Fig. 4 wherein it will be seen that a plurality of such stepped or offset portions are provided. On the inner periphery of the sleeve 17 adjacent the upper end thereof two grooves 19 and 20 are formed 75 into which the rings 15 and 16 are fitted when the sleeve 17 is disposed in the recess 14 to encircle the main body portion 10, said sleeve 17 extending between the flanges 12 and 13 as clearly illustrated in Fig. 3. On 80 the outer periphery of the sleeve 17 I provide two grooves or recesses 21 and 22 which receive the piston rings 23 and 24 that are substantially similar to the piston rings usually employed in such constructions. I have found that a preferable arrangement for the grooves 19, 20, 21, and 22 is that depicted best 85 in Fig. 2 wherein it will be seen that the grooves are alternately disposed; that is, in the arrangement depicted, so that the uppermost of the grooves opens inwardly and that the other of the inwardly opening grooves be spaced from this first named groove a distance sufficient to permit the outwardly opening grooves to be arranged on each side of 90 the second inwardly opening groove whereby the uppermost of the outwardly opening grooves will be disposed intermediate the inwardly opening grooves. The stepped arrangement 18 is preferably so arranged that 95

100

certain of the horizontally extending portions thereof will be disposed in the grooves 19 and 20 in order that the rings 15 and 16 may aid in sealing this stepped interconnection to prevent leakage thereby.

When the skirt 17 is arranged around the main body portion 10 in the manner described a spring member 25 is disposed intermediate the inner periphery of the skirt and the outer periphery of the main body portion and this spring 25 extends between the ring 16 and the flange 12 as is clearly illustrated in Fig. 3. If desired an additional spring member 26 may be provided which may be disposed to extend between the rings 15 and 16 substantially as illustrated. The springs 25 and 26 act on the skirt 17 to force the same outwardly so that when the piston construction is arranged within a cylinder this spring construction will force the split sleeve into engagement with the wall of the cylinder.

The sleeve 17 is preferably made from a material which will afford the best wearing qualities. I have found that by making the main body portion 10 from aluminum and that by making the skirt portion 17 from cast iron a highly satisfactory construction results but I wish it to be understood that my invention is not limited to the usage of such materials.

It is apparent from the foregoing description that I have provided a piston construction which will be so arranged that it will snugly fit in the cylinder bore with which it is associated. In view of the fact that the skirt portion is yieldable the likelihood of scoring will be substantially obviated. Further it is apparent that the sleeve 17 so surrounds the main body portion 10 that the wrist pin is enclosed and, therefore, the damage which might result from displacement of this wrist pin will be obviated since it will be impossible for the wrist pin to engage the cylinder wall. Further since the skirt of the piston aided by the usual piston rings will snugly fit within the cylinder bore it is apparent that leakage thereby will be substantially eliminated which will obviously increase the efficiency of the engine or other device with which the piston is associated.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a piston, a main body, a split sleeve disposed around said main body, projecting

portions at the ends of said main body for retaining said sleeve thereon against endwise displacement, said sleeve having grooves in the inner periphery thereof adjacent one end, said main body having outwardly projecting rings thereon adjacent one end thereof, said rings being disposed in said grooves when said skirt is disposed around said body, said split sleeve having grooves in the outer periphery thereof, said split sleeve having the split therein so extended that portions thereof will be disposed in certain of the grooves in said sleeve, piston rings disposed in said grooves in the outer periphery of said sleeve, and means disposed between said sleeve and said body for expanding said sleeve away from said main body.

2. A piston of the character stated including a main body having flanges extending outwardly therefrom at the ends thereof providing a recess in the periphery of said body, a split sleeve in said recess, said split sleeve having grooves in the inner periphery thereof adjacent one end, said main body having rings extending outwardly therefrom, said rings being disposed in said grooves when said skirt is disposed in said recess, said sleeve having grooves in the outer periphery thereof, said last named grooves being disposed in such a position that they will be disposed alternately with the grooves in the inner periphery thereof, said split sleeve having the stepped split therein arranged with portions thereof disposed in said grooves, piston rings in the grooves in the outer periphery of said sleeve, and elongated resilient means arranged in said recess intermediate said sleeve and said body for forcing said sleeve outwardly away from said body.

In testimony whereof I affix my signature.

HAROLD H. WAGNER.
